UNITED STATES PATENT OFFICE

THOMAS S. WILKES, OF CORVALLIS, OREGON

SURGICAL SPLINT

Application filed December 1, 1927. Serial No. 236,890.

This invention relates to surgical splints, and has as its principal object to provide an all metal splint of a minimum number of parts that will be adaptable for use on either 5 right or left limbs and adjustable in size to the requirements of youth or adult.

A further object is to provide a means of applying the pressure of the splint to any desired spot on the injured limb and a means 10 of exerting tension on the limb whenever needed to hold the fractured bones in the proper adjustment.

Due to the peculiar construction of this device, an examination of the limb may be 15 made at any time without removing the splint.

These advantages will be readily understood and appreciated by surgeons.

In the accompanying drawings I have 20 shown the preferred embodiment of my invention, but the same is susceptible of various structural changes, without departing from the spirit of my invention.

In the drawings

25 Figure 1 is a broken top view of my splint as adapted for use on the right arm;

Figure 2 is an enlarged sectional view of the hand frame regarding the same from the inside;

30 Figure 3 is a side view of the splint with the upper arm section flexed;

Figure 4 is an enlarged sectional view of the shoulder crutch, regarding the same from the inside;

35 Figure 5 is an enlarged sectional detail of the outside frame for the forearm;

Figure 6 is an enlarged cross sectional view of the roll-beaded or inside rail;

40 Figure 7 is a top view of my splint as equipped with tension bows for stretching the limb;

Figure 8 is a side view of the splint with the tension bows;

45 Figure 9 is an enlarged cross sectional view of the clip or outside rail;

Figure 10 is an enlarged detail of the elbow hinge arrangement.

In the embodiment shown, the splint is for use on the entire arm and, therefore, consists of three sections, one for the hand, as

represented at A, one for the forearm, as represented at B, and one for the upper arm, as represented at C. For the ease and comfort of the wearer, these sections are connected at the wrist and elbow by hinge joints D 55 and E respectively.

In carrying out this embodiment of my invention, I provide an inside longitudinal roll-beaded rail 1 of a length suitable for use on the forearm. This rail is formed of a single blank of metal into the shape clearly shown in Figure 6, having a V-shaped channel 2, the outer hook-flanges or hooks 3 and lips 4 projecting inwardly from the edge of the said hook-flanges or hooks 3. The outside longitudinal or clip rail 5 is essentially the same in shape and length as the rail 1, differing only in that the lips 4 are eliminated. Connecting these two rails are the transverse sections or bands 6, which have 60 their ends bent into the hooks 7 and 8 adapted to engage the hooks 3 of the elements 1 and 5. To mount these bands 6, the hook 7 is placed in the hook 3 on the inside rail, the lip serving as a stop to hold it in place. With 65 this as a pivoting point, the bands 6 are swung over so that the hook 8 slips into the hook 3 on the rail 5, as shown in Figure 9. To secure the sections 6 in this position, clips 9 are provided. They are formed of spring 70 metal, and the ends 10 being adapted to converge inwardly towards each other, the hooked ends 8 of the bands 6 are held in place. These clips are provided with two slots 11 so that they may be easily placed on the rail 5 by a suitable spreading tool (not shown) 75 having jaws adapted to engage the said slots. The transverse bands 6 are semi-circular in shape to conform closely to the contour of the arm and may be mounted alternately above 80 and below or oppositely, according to the judgment of the surgeon.

In order that the elbow may be flexed, a hinged joint E is provided. Bars 12 have their ends of a shape adapted to fit the channels 2 in the rails, being secured by a suitable bolt 13. The opposite ends of the said bars 12 are formed into circular pivoting blocks 14 having central holes 15 for the passage of the bolts 16. As it is often necessary to se- 85 90 95

cure the hinges in a set position, I provide a series of small holes 17 arranged in a circle around the edges of the blocks 14. Yoke washers 18 are adapted to fit on the bolts 16 in the usual manner, pins 19 being secured to the opposite ends of said washers. It may be seen that by placing these pins through any two opposite holes in the blocks 14, the hinge may be held in any desired angular position. 5 By unscrewing the nut on the bolt 16, the yoke washer 18 may be drawn outward disengaging the pins 19 from the holes 17 until an adjustment is made. Figure 3 shows this development clearly.

10 On the free ends of the bars 12 are slipped an inside longitudinal rail 20 of the same shape as rail 1, and being of a length suitable for use on the upper arm, and an outside longitudinal rail 21 exactly as rail 5 of a length to fit well up to the shoulder. A series of holes 22 are formed in the ends of these rails 20 and 21 adjoining the elbow hinge and the ends of the bars 12 have a corresponding series of holes. By placing the bolt 13 in any one of these holes, the length of the upper arm section may be varied. These rails 20 and 21 are also connected by transverse bands 23 similar to the bands 6 and by the clips 24 similar to the clips 9. It is obvious that this manner of connecting the rails 20 and 21 cannot be used farther up than the armpit, and for this reason special transverse shoulder sections 25, having their upper edges 26 in the shape of a reversed curve to fit the shoulder, are provided. In the upper end of the inside rail 20 is placed the V-shaped extremity 27 of the shoulder crutch bar 28, the same being held by a bolt. The upper end 29 of the bar 28 is flattened and near its edges are 25 pierced a series of square apertures 30, the portion between the edges and these said apertures 30 being rounded as shown at 31. The transverse shoulder sections 25 have their inside ends provided with a series of fingers 32 spaced equally to engage the said apertures 30. These said fingers 32 are bent around the rounded section 31 to form a hinge joint so that the outer ends of 25 may be swing over into the rail 21 and held by the 35 clip 24. This completes the arm portion of the splint and it will be easily understood that any size splint may be built up in this way.

40 The hand section is pivoted at 33 in the same manner as the elbow. The wrist bars 34 have their V-shaped ends provided with a series of holes 35 so that by means of corresponding holes 36 in the lower ends of the rails 1 and 5, the length of the forearm section may be varied. The usual bolt 43 secures this assembly. The lower ends of the bars 34 are formed into a circular shape, as before described, for the elbow joint. To these bars are pivoted by the bolts 16, yoke washers 18 and pins 19, the inside hand crutch bar 37 and the outside section

38. The said inside hand crutch bar 37 has a series of square apertures 39 near its upper and lower edges, the intervening space being rounded off at 40 as was described for the shoulder bar 28. The outside hand section is curved outwardly at 41 and formed into a V-shape to fit in the channel of the short section of the clip rail 42. A lower transverse band 43 has the extending fingers 59 on its inner edge bent around the said rounded portions 40 to form a pivoting point, the outer end being brought over into engagement with the hook on the rail 42. The upper transverse band 44, which is narrower than the band 43 and has an arcuate cut-out 45 on its upper edge to fit the contour of the hand, is hinged in a like manner to the rounded portions 40 of the element 37 and swung over into the rail 42. These bands are secured by the clips 46 and 47 as were the other bands 6 and 23.

45 In Figures 7 and 8 I show additional elements of my invention for use when the nature of the fracture necessitates a tension or pull being exerted on the arm. It consists of a forearm section B' similar to the section B of the main structure, and a hand section A' similar to the section A of the main structure. In this modification the inside bar 37 of the hand portion A' is extended in the form of a flat strip 50 and the outer section 38 extended in the strip 51 to form the hand tension bow 60. The ends of these strips are given a quarter turn as shown at 52 and have slots 53 so that a suitable clamping bolt 54 with thumb nut 55 may be placed through them. The upper arm section is removed at the hinge and the arm tension strips 56 put in its place. The ends 57 of these strips are formed into a circular shape with a hole for the bolt 16 and holes for the pins 19. The ends of these strips are given a quarter turn and have slots 53, bolt 54 and thumb nut 55 exactly as the hand tension bow 60. These bows may be placed at any width desired by the proper placing of the clamping bolt 54. When stretching is necessary, a glove is placed on the hand, the fingers being fastened to the hand tension bow 60, and a strap (not shown) placed around the elbow and fastened to the arm tension bow 61.

50 It is obvious that by minor adjustment, the splint may be adapted for use on either a right or left limb of any size. Where pressure is needed on any certain point, padding may be placed under one of the transverse sections over that point or the section may be slightly dented. By minor structural changes, the splint may be adapted for use on either the right or left leg with the same advantages that it has for use on the arms.

55 While I have herein described a preferred embodiment of my invention, it is understood that I may vary from the same in minor de-

tails of construction and assembly, not departing from the spirit of my invention as defined in the appended claims.

I claim:

- 5 1. A surgical splint including tubular side bars presenting concave faces at their inner sides and provided at their outer sides with spaced longitudinal flanges of hook formation extending laterally of the side bars in opposite directions, and a plurality of semi-circular bands having hook-shaped terminals engaging the hook-shaped flanges of the side bars, the hook shaped flanges of one of the side bars being provided with inwardly extending lips forming abutments for the adjacent ends of the semi-circular bands, and clips spanning the space between the flanges of the other side bar and securing the semi-circular bands in the flanges thereof.
- 10 2. A surgical splint composed of sections comprising tubular side bars approximately V-shaped in cross section and presenting concave faces at their inner sides and having spaced longitudinal flanges at their outer sides of hook-shaped formation extending laterally of the side bars in opposite directions, a plurality of semi-circular bands having hook-shaped terminals engaging the hook-shaped flanges of the side bars, and connecting means for the sections having substantially V-shaped members telescoping into the tubular side bars.
